TRAFFIC ACTUATED CONTROL SYSTEM

Harry A. Wilcox and John L. Barker, Norwalk, Conn., assignors to Automatic Signal Corporation, East Norwalk, Conn., a corporation of Delaware

Application July 20, 1940, Serial No. 346,517

16 Claims. (Cl. 177—337)

This application relates to traffic actuated traffic control systems and especially to systems of this kind for installation at a constricted section of roadway capable of permitting traffic flow only in one direction at a time, or at particularly wide road intersections or the like, where a relatively long time is required to clear one traffic flow beyond the point of possible conflict with another. Such a system is of use in all locations where there is a relatively long or extensive controlled area and it is desirable to clear this area of one traffic flow before right of way is accorded to a conflicting traffic flow, and to so accomplish this without imposing unnecessary delay to the conflicting traffic flow.

In accordance with the invention a traffic control system of this character is provided in which the right of way is accorded to either approach to the relatively long zone of interference in response to traffic actuation on such approach, but before such accord of right of way to the first approach the right of way is interrupted on the other approach and right of way is maintained interrupted on the first approach for sufficient time to clear from the zone of interference any traffic which may have entered from such other approach, and reduction of this period of interruption of right of way to both approaches is provided in accordance with the amount of time which may have elapsed after the last moving vehicle entered from the first approach before the arrival of the first vehicle on the other approach.

The system preferably provides for the right of way to remain on the approach on which traffic has last arrived in absence of any traffic on the other approach and provides for the prolongation of right of way for a brief time period following the arrival of each vehicle having right of way, and also provides that in event of continued prolongation of right of way by closely spaced vehicles on one approach a maximum limit to such right of way will become effective upon arrival of any vehicle on the other approach.

In accordance with the preferred embodiment of the invention disclosed herein, a potential overall clearance period is timed from the arrival of each vehicle with the prolongation of right of way by such vehicle on one approach and becomes an actual right of way interruption clearance period only in event of arrival of a vehicle on the other approach and then only for the balance of such overall time remaining after arrival of the latter vehicle.

The system of the present invention has par-

ticular value at a long narrow bridge or tunnel or a relatively narrow section of curved roadway where it is unsafe or impossible to permit traffic to pass in two directions for example.

5 Traffic actuated traffic control systems have in the past been built for numerous types of installation and for many varied conditions of operation. For example systems of the traffic actuated type for displaying right of way to conflicting flows of traffic alternately and successively for varying time periods in accordance with actuations of traffic detectors in the lanes of flow are well-known. Long in use also are systems which provide that a unit of traffic which actuates a detector during a change of right of way, or "amber signal", period procures for itself extension of the change period beyond the normal duration of the period for safe passage of the actuating traffic unit through the intersection before right of way is accorded to the opposing traffic flow.

10 The present system, however, is adapted particularly for controlling for example traffic moving along a roadway having a constricted section of considerable length as caused for instance by the presence of a narrow bridge through or over which traffic may safely be permitted to flow in only one direction at a time. Traffic control signals mounted at the ends of the constricted area are governed by a controller under the influence of traffic detectors set in the approaches to the constricted section, and in the absence of other traffic a single vehicle actuating a detector immediately receives accord of right of way following the usual brief amber change period, if the control is not already showing right of way for the vehicle as a result of prior traffic actuation on the same approach. Succeeding vehicles entering the restricted section are each assured a minimum time period for clearing the area and although other vehicles which arrive meanwhile on the opposite approach may affect the controller to interrupt the right of way signal being shown in the event of a sufficient brief time

15 spacing appearing between vehicles on the first approach, right of way cannot be accorded safely to such opposite approach and right of way is thus denied to both, until the minimum clearance period for the last vehicle in the area has expired. In accordance with the invention, if there should be no arriving vehicles on the said opposite approach until the minimum clearance period for the last vehicle to enter the area from the first approach has expired, there will be no 20 period in which right of way is denied to both

approaches and accord of right of way will be transferred directly, following the usual brief amber change period.

A vehicle arriving on one approach during a continuous flow of traffic from the opposite approach will initiate operation of a maximum limit timer to ensure that in the event of the opposing traffic continuing, right of way will be interrupted on such opposite approach after a maximum period and, following the elapse of the full clearance interval as described, right of way will be accorded thereafter to the waiting vehicle. In this event the controller will automatically re-transfer right of way for permitting resumption of passage of the continuous flow which had been cut off. Each transfer of right of way from one approach to the other always establishes accord of right of way for at least a minimum period which is capable of being prolonged by additional vehicle actuation on the lane having right of way within the right of way period.

It will be appreciated therefore that each vehicle entering the restricted section during the right of way period for such vehicle by the present system is assured of safe travel time period in which to pass through the area, and that traffic approaching the area will under no conditions be delayed when the area is free of traffic, and that under all conditions of arriving traffic the controller will govern movement through the area expeditiously, safely and efficiently.

It is an object of the invention, therefore, to provide a traffic actuated traffic control system for constricted roadway sections, wide intersections and the like which shall transfer and accord right of way to interfering flows of traffic for varying time periods in accordance with traffic detector actuations and which shall provide a minimum clearance time period for every vehicle entering the controlled area before the completion of which period right of way cannot be accorded to a conflicting traffic flow.

It is a further object that a system of this character be provided which shall deny right of way on all approaches to the controlled area during any portion of the minimum clearance period which remains after detector actuation on an approach not having right of way before transferring accord of right of way to the approach of the actuation, thus safeguarding the completing of passage of any vehicle proceeding through the area and without causing delay to the vehicle on the approach not having right of way if not required by the actual presence of traffic in the area.

It is a further object of the invention to provide an improved traffic right of way control system for interfering traffic lanes having a relatively long zone of interference so as to require a relatively long time for the last vehicle entering this zone from one lane during the right of way period of that lane to clear through this zone of interference before right of way can safely be accorded to the other lane, and in which a clearance period is provided in which right of way is interrupted to both of the interfering lanes concurrently for sufficient time to clear the last vehicle entering on a right of way signal from one approach before right of way is accorded to the opposite approach.

Another object is to provide a traffic control system having a relatively long clearance period of interruption of right of way normally appearing upon transfer of right of way from traffic on one approach to traffic on another, inter-

fering traffic approach, and in which the time length of this right of way interruption clearance period is automatically reduced in accordance with the amount of time the right of way has remained on one approach since arrival of the last vehicle on that approach, so as not to delay unnecessarily a vehicle arriving on such other approach at a time when no vehicles are arriving or have recently arrived on the first approach 10 which has had the right of way.

It is an object of this invention to provide a traffic control system for interfering traffic lanes in which the zone of interference between the two lanes is relatively long, in which right of way 15 is accorded alternately to the two lanes respectively in response to traffic arriving in the respective lanes, said system including the provision of a period of interruption of right of way in both lanes after termination of accord of right of way 20 in one of the lanes and before accord of right of way to the other lane in response to traffic in the latter lane, with the period of interruption of right of way to both lanes having an ultimate length sufficient to permit a vehicle to clear 25 through the whole zone of interference but having this period reduced from such ultimate length in accordance with the amount of time which may have elapsed from the arrival of the last vehicle on the approach having right of way before the arrival of the first vehicle on the other lane while right of way is interrupted therein.

It is an object of the invention to provide a traffic control system for the accord of right of way alternately to two approaches to a relatively long zone of interference in which a short period of extension of right of way is provided following the arrival of each vehicle on the approach having right of way and in which an overall clearance time period is provided following the arrival of each such vehicle and of considerably greater length than the right of way extension time period, and in which right of way is interrupted in the first approach, in response to expiration of the right of way extension period upon or after the arrival of the first vehicle on the second approach, with the time length of such interruption of right of way to both approaches representing the difference between the overall clearance period and the extension period.

It is an object of the invention to provide a traffic control system for interfering traffic lanes in which there is a relatively long zone of interference between the lanes for traffic to clear and 55 in which the right of way is accorded alternately to the lanes respectively, said system providing a short period timer for prolongation of right of way for a brief period from arrival of each vehicle in the lane having right of way and at the 60 end of which brief period the right of way on the first lane will be interrupted in response to traffic arriving on the second lane, and providing a second timer to time a longer time period than the first from arrival of each vehicle having the right of way, with this longer time sufficient to permit such vehicle to clear through the entire zone of interference, and to delay accord of right of way to the opposite lane in response to arrival of the first vehicle in the latter lane so that a period 65 of interruption of right of way to both lanes will ensue between termination of the time period of the first timer and termination of the time period of the second timer but only of sufficient length to clear the last vehicle arriving with the right of way, whereby any vehicle arriving on a lane not 70 75

having right of way while right of way is on the other lane will obtain transfer of right of way substantially immediately to its lane, if no car has arrived on the right of way lane for a prior period exceeding the clearance time.

It is an object of the invention to provide a traffic signal system for interfering traffic lanes in which there is a relatively long zone of interference for traffic from one lane to clear so as not to interfere with traffic entering from the other lane, and in which the usual green, yellow and red traffic signals are provided with the green signal displayed to only one lane at a time while the red signal is displayed to the other and with the yellow signal displayed after the green and before the red to give a brief period of warning to moving traffic that is about to be stopped, and in which an overall clearance period is timed from the arrival of each car on the lane having the right of way to delay transfer of the green signal to the other lane for sufficient time to permit such vehicle on the first lane to clear the zone of interference and a shorter period is also timed for prolongation of the green signal from the arrival of such vehicle arriving on the first lane for the green signal to be changed to yellow on the first approach substantially immediately in response to a vehicle on the other approach upon entry of the vehicle on the first approach into the zone of interference if there are no immediately following vehicles on this approach, and for the yellow signal to be displayed for a very brief period after which the red signal will be displayed to the first approach as well as maintained in the second approach for the balance of the overall clearance time.

The nature of the invention will be clear from the following description of one embodiment together with the accompanying figures of the drawings, in which:

Figures 1 and 2 together comprise a circuit diagram of an embodiment of a controller according to the invention, and right of way signals and traffic detectors for governing movement of traffic in one direction at a time through a constricted section of roadway, where the roadway passes across a narrow bridge for example.

The roadway shown is adapted generally to accommodate traffic travel in both directions except for a section in which the roadway is constricted by its passage through a bridge BR where the narrowed roadway can safely carry only a single lane of traffic. As represented in the drawings by the section or break at the center part of the bridge the narrow constricted section may be of considerable length. The usual green, amber, and red signal indications may be presented by the signals GA, AA, and RA for traffic on approach A from which traffic enters the restricted section from the left toward the right side of the Figure 1, and by the signals GB, AB, and RB for traffic on approach B from which traffic enters the bridge area from the right toward the left side of the drawings. Traffic actuatable devices or detectors D1, D2 which may be of the pressure-sensitive type or magnetic type or other suitable type adapted to operate on electric circuit when actuated by a vehicle are located in the approaches to the restricted area preferably some distance in advance of the signals. In the present embodiment the detectors are illustrated as switches adapted to be closed by actuation.

The control apparatus for the signals is conveniently mounted near one set of signals and

connected to the signals and to the detectors as indicated in the drawings.

It will be appreciated that the traffic control system disclosed may be used advantageously in many types of installations besides the one-way restricted traffic area shown. For example it may be used at intersections of two particularly wide roads. It is advantageous for use at other types of intersections, such as the crossing of a road of normal width with a particularly broad road, or wide crossings of more than two roadways, or in fact wherever it is desired that an assured clearance period of considerable duration for the last vehicle entering the controlled area be provided before right of way is accorded to a conflicting flow of traffic without imposing needless delay to such conflicting traffic when no vehicle is in the restricted area.

The operation of the system will first be considered broadly and described briefly in relation to various traffic conditions before considering the operation of the system through one cycle of the signals in more detail as described subsequently in this specification.

For the present brief description it will be assumed that the several control switches PA and PB are open and ARS and BRS are closed as shown in Fig. 1. It will also be assumed for purposes of illustration that the distance from either detector D1 or D2 through the restricted area or interference zone across the bridge BR is about 600 feet, and that the low range of speed through this zone is 40 feet per second or about 27 miles per hour. It will be understood that these figures are merely illustrative and that the actual figures may be considerably lower or much higher at various locations to which this system may be applied. Under these conditions the vehicle will require 15 seconds to clear from the detector through the entire interference zone.

In the condition of absence of traffic on both approaches and in the zone of interference the right of way will remain on the approach on which the last previous vehicle arrived and cleared through the zone of interference. Assuming that the last previous vehicle arrived on approach A then the right of way will remain on approach A with the green signal displayed there and the red signal displayed to approach B. These signals will remain continuously displayed in this fashion in absence of any traffic on approach B whether or not there is any traffic on approach A.

In case a vehicle should arrive on approach B while right of way is on approach A but in the absence of traffic on approach A for an appreciable time such as 15 seconds for example prior to the arrival of such vehicle on approach B, the red signal on approach B will remain displayed as before but the green signal on approach A will be extinguished and the amber signal on approach A will be displayed for a brief time after which the amber signal will be extinguished and the red signal displayed on approach A. Up to this moment the red signal has remained on approach B but this signal is now substantially immediately extinguished and the green signal on approach B displayed. The green signal remains displayed on approach B with the red signal on approach A for a minimum time period controlled by a timing device and this signal display thereafter continues in absence of arrival of any traffic on approach A.

Assuming the original signal display again with

right of way on approach A and considering the case of the arrival of a vehicle on approach B immediately after arrival of a vehicle on approach A, the signal display will remain unchanged with the right of way maintained on approach A for a short time period from the arrival of the vehicle on A. The right of way is thus extended on A for this short time period for the protection of this vehicle on A. In absence of further vehicles arriving on A the green signal on A will be extinguished at the end of this short extension time period and the amber signal will be displayed on A while the red signal remains on B as before. After a brief amber period as before, the amber signal will be extinguished and the red signal displayed on approach A. Normally the short right of way extension period and the following amber period will consume only a few seconds and assuming a total overall clearance period of 15 seconds the red signal is maintained on approach B in addition to the red signal on approach A for a further time period representing the remainder of the overall clearance period, as measured by a timing device. After this clearance period has been completed the red signal is extinguished on B and the green signal is displayed there for at least a minimum period as before described.

Returning to the original signal display again with right of way on approach A and considering the case of arrival of a vehicle on B at a time of a continuous succession of closely spaced vehicles arriving on approach A, a maximum time limit will become effective as a result of arrival of the vehicle on B so that right of way cannot be maintained beyond such maximum time limit. As each of the succession of vehicles on approach A actuate detector D1 within such maximum limit the right of way will be prolonged on approach A for the short extension period, and assuming that the vehicles are so closely spaced that each vehicle arrives within the short extension period provided by the vehicle preceding it, the right of way will be maintained on approach A up to the maximum limit, and at this limit the green signal on A will be extinguished and the amber signal displayed for a short period as before described, after which the amber signal will be extinguished on A and the red signal displayed there. The operation of the maximum limit in terminating right of way on A will ordinarily occur within a moment of actuation of detector D1 by a vehicle on A and thus substantially the full overall clearance time is required for such vehicle or for the last vehicle entering from approach A so that the red signal is maintained on approach B as well as on approach A after the amber period for A for substantially a full clearance period after which the green signal is substituted for the red signal on B as previously described, but in this case the right of way will be returned to approach A at the end of the minimum period on B, in absence of further vehicles on B, so as to care for the traffic on A interrupted by the maximum. If further vehicles arrive on B to prolong the right of way on B the right of way will be returned to A after the proper B clearance period at the end of either the B right of way extension period or B maximum period depending upon how long vehicles continue to arrive on B.

With switches ARS and BRS both closed as assumed, the system is symmetrical with respect to the two approaches A and B and therefore the

transfer of right of way from approach B to approach A will take place in the same fashion for various traffic conditions as previously described for transfer of right of way from A to B under such traffic conditions but with these conditions reversed as to the two approaches.

The several features of operation just described with respect to various traffic conditions are provided in accordance with the present preferred embodiment of the invention by the provision of a minimum right of way timer device, a right of way extension timer device having a relatively short time period, a maximum right of way timer device having a relatively long time period, and an overall clearance period timer device also having a relatively long time period but not necessarily of the same length as the maximum timer period. This clearance time period is ordinarily of shorter length than the maximum time period for zones of interference of ordinary length although it would be possible under conditions of an extremely long zone of interference and relatively light traffic that it might be desirable to have the maximum time period shorter than the overall clearance time period. A timer device is also provided for the amber period. The right of way extension period timer and the overall clearance period timer are each reset to restart their timing period responsive to each traffic actuation by vehicles arriving with the right of way and in the present preferred embodiment these timers are reset at the moment of actuation and measure their time period from that moment, but it will be appreciated that similar but somewhat inferior results may be obtained by the use of a recycling type of timer which will be actuated in each successive extension time period to add another time period after completion of the current time period.

Referring now to the drawings for a more detailed consideration of the present embodiment of the invention the traffic signal controller represented therein comprises a number of sets of contacts for controlling the right of way signals and circuits for timing the display periods of the signals, these contacts being operated by a cam shaft which is moved step-by-step through a cycle by means of a solenoid and ratcheting mechanism. The stepping of the solenoid is governed by a timing circuit employing a gaseous discharge tube-condenser timer arranged to have its time periods varied under control of the vehicle detectors located in the approaches to the restricted area. Under a number of circumstances more than one time period is simultaneously timed and the present controller utilizes a plurality of timing circuits for this purpose.

The controller is arranged to operate from an alternating current supply 1, 2. To provide direct current for the timing circuits a transformer 3 supplies rectifier 4. The ungrounded AC lead 2 is denoted by a plus in a circle and the ungrounded DC lead 5 is denoted by a plus in a square. The common grounded AC and DC lead 4 is represented by a minus in a circle and square. Cam-operated contacts are shown aligned near the right of the drawings and the positions of the cam shaft in which each contact pair is closed in the six position cycle are indicated in the chart at the extreme right of the drawings.

In describing operation of the system it will be assumed first of all that the cam shaft is in position 6 the A approach right of way period and that there is no traffic on either approach. It

will also be assumed that switches PA and PB, which under certain conditions explained fully below simulate the operation of the detectors, are open, and that switches ARS and BRS are closed, with switches SWA and SWB in the position shown.

Circuits are completed in this position of the cam shaft from AC plus lead 2 through the approach B red or stop signal RB via cam contact C22 to common minus lead 1, and through the approach A green or go signal GA via cam contact C9 and contact rr3 of deenergized relay RR to AC minus lead 1. Under the condition of no traffic assumed, a charging circuit for condenser QJ is completed from DC plus lead 5 via high resistance VA, cam contact C5 lead 10 condenser QJ, resistance ZJ to minus lead 1. Condenser QJ, over a time period proportional to the amount of control resistance VA in circuit, is charged to a voltage in excess of that required to cause discharge through the gaseous discharge tube FJ, but as the circuit through the tube FJ paralleling the condenser QJ via lead 14, relay contact rr9, lead 15, relay contact K3, tube FJ, relay J, lead 16, relay contact bd3, cam contact C28, lead 17 to AC minus lead 1, is open at contact bd3 in the absence of detector actuation, no discharge through the tube FJ can occur at this time.

If now a vehicle arrives on approach B actuating detector D2, relay BD is energized by a circuit from plus lead 2 via lead 11, relay coil BD and detector D2 to minus lead 1, and relay BD is locked-in over contact bd1, lead 12, cam contact C18, lead 13 to minus lead 1. Operation of the relay BD enables the circuit previously traced paralleling condenser QJ to be completed via contact bd3. Since the voltage across condenser QJ now exceeds the flash potential of tube FJ as result of completion of its charging period as previously described, the circuit through the tube becomes conducting and relay J is momentarily energized by the discharge of condenser QJ through it and a circuit is completed from minus lead 1 via relay contact j2, cam contact C6, lead 18, through solenoid S to plus lead 2, energizing solenoid S. The momentary energization and deenergization of solenoid S advances the cam shaft one step to position 1.

In position 1 the A approach green light GA is extinguished by breaking of cam contact C9 and the A approach amber, or right of way change signal, AA is displayed by closure of cam contacts C10. The duration of the period is timed by the charging of condenser QK from DC plus lead 5 through resistance LA, via cam contact C3, contact ad6 lead 19, QK, resistor ZK to minus lead 1. As soon as QK reaches the flash voltage of tube FK in parallel with the condenser through relay K, tube FK becomes conducting and relay K is momentarily operated by discharge of condenser QK, and at contact K4 circuit for energizing solenoid S is completed to advance the cam shaft into position 2, the B approach initial green period.

In addition to causing operation of the solenoid the momentary energization of relay K completes a circuit at contact k1 for energizing relay RR over cam contact C4, lead 20, closed switch ARS.

The advancement of the cam shaft to position 2 causes extinguishing of the A approach amber signal AA by opening cam contacts C10, and energization of the A red signal RA by closure of cam contacts C11 in position 2. B red signal RB is maintained energized despite the opening of 70 75

cam contacts C22 by circuit through cam contacts C20 and closed contact rr2. Thus the normal signal indications for cam shaft position 2 are superseded for the moment by stop signals to both approaches. However under the traffic conditions here assumed of no traffic having entered the restricted area from the A approach for a considerable time period the denial of right of way to both lanes is immediately ended by deenergization of relay RR as explained below. The all-red period under this condition of immediate deenergization of relay RR is of substantially no duration whatever, being of the order of a fraction of a second, and the normal signal indications for cam shaft position 2 are then initiated, i. e., A approach red signal RA is then energized over cam contacts C11 and B approach green signal GB is then energized via cam contacts C20 and back contact rr1.

The energization of relay RR upon the terminating of the A amber signal period in position 1 occurs when the amber period timing ends the period by operation of relay K which at contact k1 completes circuit to energize relay RR from plus lead 2, relay RR, contact k1, cam contacts C4 (closed in position 1), lead 20 and closed switch ARS as previously described. Relay RR is locked-in over contact rr5, contact j1 to minus lead 1. The subsequent deenergization of relay RR to terminate the all-red display in position 2 is dependent upon the timing circuit involving condenser QL which is charged gradually during preceding cam shaft positions 6 and 1. This charging circuit extends from DC plus lead 5 over resistance RRA, cam contacts C1, lead 21, condenser QL to minus lead 1. Also, in positions 6 and 1, a resetting circuit for this condenser is prepared from minus lead 1 via lead 22, contact rr7, contact ad2 (open), lead 23, low resistance ZRA, and cam contacts C1 to condenser QL. The charge on QL accordingly is reduced to substantially its zero or starting potential by each successive vehicle entering the restricted area from approach A and actuating relay AD in cam shaft positions 6 and 1 thereby closing the resetting circuit at contact ad2 and momentarily discharging condenser QL.

In the case assumed where there is no vehicle actuation of approach A detectors condenser QL charges in positions 6 and 1 without being reset. Operation of relay RR as the cam shaft is advanced to position 2 completes an operating circuit for the condenser QL via lead 21, contact rr8, lead 15, contact k3, tube FJ, relay J, lead 16, contact bd3, cam contacts C28, and lead 17 to minus lead 1, and since there has been no resetting of condenser QL by vehicles the charge on condenser QL has exceeded the flash voltage of tube FJ and relay J operates to cause immediate deenergization of relay RR by breaking the holding circuit of the latter at relay contact j1.

It will be apparent that in the event of a vehicle from A approach having entered the restricted area during the A approach right of way period in position 6 or during the following brief amber signal period in position 1, condenser QL would have been reset and could not therefore attain the flash voltage of tube FJ for the time period required to recharge condenser QL, which time period is set for an overall clearance period of sufficient length to clear the last entering vehicle through the whole restricted area. If it is assumed as before that a vehicle will require 15 seconds to clear from the detector through the entire restricted area for this particular location,

the resistance RRA or RRB for the A and B approaches respectively, or for both approaches if the conditions were the same in opposite directions as to required clearance time for traffic, would be adjusted to provide for charging condenser QL to the flash voltage of tube FJ in 15 seconds and thus provide an overall clearance period of 15 seconds.

Accordingly if a vehicle entered from A approach during the A right of way period in the cam shaft position 6, for example, the condenser QL would be reset to restart its timing of this 15 second overall clearance period at the moment that this vehicle crossed the A detector D1. In absence of further vehicles on A approach for the moment the A right of way period would be terminated after a few seconds by completion of the timing of condenser QJ in position 6 and the amber signal period in the following position 1 would be terminated by completion of timing by condenser QK after a brief period of 1 to 3 seconds for example. This would leave a balance of several seconds of the overall clearance period to be timed by condenser QL in position 2 while red signals are displayed to both A and B approaches as a result of the energization of relay RR at the end of the amber period in position 1. Accordingly the red signals on both approaches would continue to be displayed in position 2 for the balance of this overall clearance period, until condenser QL attains the flash potential of tube FJ and operates relay J to instantly deenergize relay RR which in turn at its contact rr2 will extinguish the B red signal RB and at its contact rr1 will light the B green signal GB.

It will also be apparent that if a vehicle arrived at the detector D1 in the A approach just a little too far behind the preceding vehicle to continue to hold the right of way on the A approach against a vehicle waiting on the B approach for example, condenser QJ would have completed its timing in position 6 and the cam shaft would have been shifted ahead to position 1 and this particular vehicle would cross detector D1 on A approach during the A amber period. The reset circuit for condenser QL controlled by the A detector D1 at its relay contacts ad2 is still effective in position 1 since cam contacts C1 and relay contacts rr1 remain closed, and thus this particular vehicle resets condenser QL again in position 1 and the overall clearance period is timed from position 1 on, thus giving an all red clearance period in position 2 of substantially the whole length of the overall clearance before deenergization of relay RR as previously described.

The deenergization of relay RR causes no movement of the cam shaft but extinguishes the B approach red signal RB and energizes the B approach green signal GB as previously described.

The initial B approach green period is now timed by condenser QK from DC plus lead 5 over resistance IB, cam contacts C13, lead 24, contact rr10, which has closed upon deenergization of relay RR, and leads 25, 26 through condenser QK. When the charge on condenser QK has attained the flash potential of tube FK, the latter becomes conducting and operates relay K in parallel with the condenser QK, and at contact k4 the operating circuit for the solenoid S is momentarily completed, all as previously described, to advance the cam shaft to position 3, the B approach vehicle interval period.

This advance to position 3 produces no change in the signal lights but the condenser QJ is now

charged over resistance VB, cam contacts C16, leads 10, 14. Moreover relay BD is deenergized by the opening of its locking circuit at cam contacts C18, and by the closure of cam contacts C25 a circuit for shunting or resetting condenser QJ upon further B approach detector actuations is prepared extending via lead 17, through cam contact C25, lead 27, contact bd4—when closed—and lead 29, and low resistance ZY. It will be noted that since the lock-in circuit for relay BD is open in this period at cam contact C18 relay BD is only operated in this period momentarily while a vehicle is actually traversing the detector and that the resetting of the condenser QJ and resulting extension of the timed period is dependent on the speed of the vehicle, being greater for a slow moving vehicle than for a fast one. The degree to which the extension is variable by vehicle speed is controlled by selection of the value of resistance ZY in relation to the capacity of condenser QJ and the time length of the momentary vehicle actuation, according to the well known condenser-resistance-time discharge characteristic.

If there is no further traffic on the B approach relay BD will remain deenergized and contact bd4 will remain open so that condenser QJ will charge without being reset. However until relay AD is operated by a vehicle traversing the A approach detector D1 no operating circuit paralleling the condenser QJ through tube FJ and relay J will be completed for operation of relay J and consequent operation of the solenoid by the latter. This operating circuit for relay J extends from the condenser QJ, lead 14, contact rr9, lead 15, contact k3, tube FJ, relay J, lead 28, contact ad3, lead 27, and cam contacts C25 to minus lead 1.

Vehicle actuation of an A approach detector energizing relay AD, in addition to completing the above described operating circuit for relay J, will also initiate operation of a maximum timing circuit involving condenser QK. This latter circuit ensures that in the event of further vehicles thereafter successively arriving on the B approach and resetting condenser QJ by momentary closures of contact bd4 via resistance ZY in the manner outlined above, the waiting vehicle on A approach will not be delayed for greater than a preset maximum time. The maximum timing circuit for charging condenser QK extends over high resistance MB, cam contacts C26, contact ad5, lead 19, and condenser QK, and the resistance ZK to minus lead 1, and is initiated by closure of contact ad5. If the spacing of B approach vehicles is sufficiently close to maintain condenser QJ below the flash voltage of tube FJ until condenser QK reaches the flash voltage of tube FK, the latter will operate relay K to effect advancement of the cam shaft into position 4, the B approach amber or right of way change period.

Whenever the cam shaft is advanced from position 3 by action of the maximum timing circuit relay K, thereby interrupting a stream of vehicles on the B approach, provision is made to ensure that without further operation of the B approach detector right of way will be returned to the B approach. This circuit extends from minus lead 1 over contact k2 and cam contacts C27, energizing relay BD at the end of position 3; a lock-in circuit for relay BD being established over solenoid contact S1 and relay contact bd1 while the solenoid advances the cam shaft to position 4, where the lock-in circuit then

extends over cam contacts C18 and contact bd1.

Movement of the camshaft through the remaining positions 4, 5, 6 comprising the B amber period, and A approach right of way periods respectively, is similar to that described for positions 1, 2 and 3. In position 4 the B approach amber signal AB is energized over cam contacts C21 and the A approach red signal RA over cam contacts C11. Condenser QK is charged over resistance LB, cam contacts C14, back contact bd6, lead 26 to condenser QK. If right of way is being forcibly removed from the B approach thus intercepting a stream of traffic an extended amber period is provided by the inclusion of resistance ZB in the charging circuit since contact bd6 would be open in this circumstance. Similar provision is made in the A approach amber period at contact ad6 and resistance ZA.

As the cam shaft is advanced into position 5 at the end of the B amber period, relay RR is energized via closed switch BRS, cam contacts C15, contact k1. At contact rr4 the A approach red signal RA is maintained and at cam contacts C22 the B approach red signal RB is energized. Condenser QL is under charge in periods 3, 4 and 5 via resistance RRB, and cam contacts C12 and is subject to reset in periods 3 and 4 by B approach traffic entering the restricted area over contacts rr6, bd2, low resistance ZRB. In position 5 as soon as condenser QL attains the flash voltage of the tube FJ which is connected in parallel with the condenser in position 5 by contacts rr8 which are then closed, the all-red period is terminated as relay RR is deenergized at j1; and at contacts rr3, rr4 the A green signal GA is energized in place of the red signal RA. The cam shaft is not advanced.

The A approach initial green period is now timed by the charging of condenser QK over resistance IA. Cam contacts C2, lead 24, contact rr10, leads 25, 26, and is concluded by operation of relay K which at k4 energizes solenoid S to cause movement of the cam shaft to position 6, the A approach vehicle interval period, where there is no change in the signals.

The resettable or vehicle interval is timed in position 6 by charging condenser QJ over resistance VA, cam contacts C5, subject to resetting by A approach vehicles crossing detector D1 and momentarily shunting QJ by low resistance ZY at contact ad4. B approach detector actuation initiates the maximum timer circuit of condenser QK, charging via resistance MA, cam contact C23 and contact bd5, and also places tube FJ and relay J in parallel with condenser QJ by connecting relay J at lead 16 to minus lead 1 by contact bd3 via cam contacts C28 and lead 17.

In position 6 the charging circuit for condenser QL is again completed via resistance RRA and cam contacts C1, and its reset circuit via contacts rr1, ad2 and low resistance ZRA to prepare once more for determining the extent of the subsequent all-red signal period when right of way is transferred to the B approach. A complete cycle of operation of the controller has now been described.

Upon each operation of the solenoid S condensers QJ and QK are reset respectively by operation of contacts S2 and S3 near the limit of the solenoid stroke, via small limiting resistances ZJ and ZK respectively, to assure that the condensers will be fully discharged and ready to commence their next timing actions following each operation of the solenoid to step the cam shaft from one position to the next. Condenser QL

which is charged cumulatively over several periods at a time is discharged in initial green periods 2 and 5 by low resistances ZRA and ZRB respectively. The same resistances serve to reset condenser QL upon A approach vehicle actuations in positions 6 and 1 and upon B approach vehicle actuations in positions 3 and 4 as previously explained. For example in position 2 condenser QL is discharged by a circuit from QL over lead 21, cam contacts C1, low resistance ZRA, lead 323, contacts ad2, rr1, and lead 22 to minus lead 1.

The switches PB and PA are so-called arterial or recall switches and each when closed assures that right of way will be returned to its associated approach in the absence of traffic thereon. Their effect with either one switch closed alone is to simulate the action of the detectors when their respective approaches are not receiving right of way, by energizing relay AD in B right of way positions 2 and 3 through switch PA or relay BD in A right of way positions 5 and 6 through switch PB. These switches therefore produce no prolonging of right of way periods. With both switches closed the controller will operate to accord right of way cyclically for minimum periods extendable by traffic actuation. If the setting of resistance RRA is for a period in excess of the sum of vehicle and amber intervals VA and LA, and that of resistance RRB for a period in excess of the sum of the periods produced by VB and LB, all-red periods equal to their excess differences will be interposed in the cycle when no traffic is passing.

In some installations it may be desired to provide an overall clearance interval for travel from only one direction of approach and in such instance one of the switches ARS or BRS is opened corresponding to the phase on which it is desired to omit the assured overall clearance and all-red period. If for example the overall clearance period for the A approach is omitted switch ARS is opened. This renders relay RR incapable of operation in position 1 at the end the A approach amber interval, the all-red signal display in position 2 is thus eliminated and the approach B initial green signals are displayed and timed immediately in position 2. The all-red interval following approach B amber would in this instance be interposed as usual since switch BRS is assumed to remain closed. For ordinary operation at a restricted zone or bridge BR however both switches ARS and BRS would be closed as shown.

In certain instances when one of switches ARS or BRS is opened the arterial or reverting switch for the opposing approach may be closed thus ensuring that in the absence of traffic right of way will always be returned to one approach and that an assured overall clearance period will be accorded to traffic entering the restricted area on such approach, and that following transfer of right of way to the opposite approach the right of way will subsequently be automatically retransferred to the first approach.

Summarizing it will be appreciated from the above description that in the present controller operation may be obtained so that following the entrance of each vehicle to the restricted area during the right of way period for such vehicle a predetermined time period must have elapsed before traffic on the second or conflicting approach may receive the green signal in response to actuation. This period is the time required for condenser QL to charge to the flash potential of tube FJ following resetting of the condenser QL by

the said vehicle. If the full period timed by condenser QL is completed prior to actuation on the second approach, right of way will be accorded to the second approach immediately upon actuation thereon following the usual brief amber period. If, however, the full period of condenser QL has not been so completed when such actuation on the second approach occurs, condenser QL will not be charged sufficiently to discharge through relay J via contact $r\bar{r}8$ and therefore an all-red interval is introduced following the amber period until the overall clearance period is completed by the charging of condenser QL to the flash potential of tube FJ.

During the all red period the red signal is maintained displayed to the second approach to prevent vehicles thereon from proceeding into the area, and red is also shown to the first approach to prevent any vehicles subsequently approaching on the first approach from entering the restricted area. The all red interval, terminated as soon as condenser QL discharges through tube FJ and relay J, is thus of sufficient duration for the last vehicle entering the area from the first approach to complete its passage through the area, and the actuating vehicle on the second approach will be delayed only so long as any vehicle, travelling at average speed, remains in the restricted area.

It will be further appreciated that by opening either of switches ARS or BRS the overall clearance period following the right of way period on the phase corresponding may be eliminated. This type of operation is desirable when the controller is installed for instance at the intersection of a very wide divided highway with a crossroad where a long clearance period is required only on the crossroad for vehicles to clear the long crossing of the wide highway.

In the embodiment of the system as previously described herein it will be noted that an amber signal is displayed for a short period following the green signal period and before the red signal period on each lane, which is a very widely used sequence of signal colors. It will be understood, however, that other suitable sequences of signal colors may be used with minor rearrangements of the signal connections or cams. For example, if it is desired to have a direct change from green to red and to omit the amber signal as is the practice in some localities this can be accomplished by changing the position of switches SWA and SWB appearing in Fig. 1. As shown in Fig. 1 these switches are in position to provide the amber signal as previously described, and for this purpose switch SWA connects lead 35 to lead 33 and the A amber signal whereas switch SWB connects lead 32 to lead 31 and the B amber signal.

If it is desired to omit the amber signal and to have the red signal come on at the beginning of what would be the amber signal period then switch SWA is shifted to connect lead 35 to lead 34 and the A red signal RA and switch SWB is shifted to connect lead 32 to lead 30 and the B red signal RB, and the amber signals AB and AA can be omitted. It will be observed from the cam position chart that this shift in the position of switches SWA and SWB will cause the display of signal RA in position 1 as well as in position 2, 3 and 4, for example, and will cause signal RB to be displayed in position 4 as well as 5, 6 and 1.

In some localities it is the practice to have a dark period with no signals displayed on a traffic lane following the green signal period on that

lane and before the red signal period on that lane and while the red signal is maintained on the opposite lane. It will be noted that a sequence of this type can be provided by omission of the amber signals AA and AB with the switches SWA and SWB in the positions shown in Fig. 1, and with this arrangement the signals will be dark on approach A in cam shaft position 1 and on approach B in cam shaft position 4.

It will be understood by those skilled in the art that other changes in the design or construction of the disclosed embodiment of the invention, such as for example the substitution of mechanical timers or other electronic timers for the particular condenser-timing arrangements shown, or other substitutions of equivalents for various parts or rearrangements thereof, may be made without departing from the spirit of the invention as defined in the appended claims.

We claim:

1. A traffic control system for interfering traffic lanes in which the zone of interference between the lanes is relatively long, including a right of way signal controller for according right of way alternately to the lanes respectively in response to traffic arriving in the respective lanes and to interrupt right of way in the other lane when right of way is accorded to one lane, means forming a part of said controller to interrupt right of way in both lanes after termination of accord of right of way in one lane and before accord of right of way to the other lane in response to traffic arriving in the latter lane, and means for timing such interruption of right of way to both lanes to provide an ultimate length of time sufficient to permit a unit of traffic to clear through the zone of interference but to reduce the time of interruption of right of way to both lanes from such ultimate length in accordance with the amount of time the right of way may have remained on the one lane after arrival of the last prior vehicle there and before arrival of the first vehicle on the other lane while right of way is interrupted in the latter lane.

2. A traffic control system for interfering traffic lanes in which the zone of interference between the lanes is relatively long, including a right of way signal controller for according right of way alternately to the lanes respectively in response to traffic arriving in the respective lanes and to interrupt right of way in the other lane when right of way is accorded to one lane, means forming a part of said controller to interrupt right of way in both lanes after termination of accord of right of way in one lane and before accord of right of way to the other lane in response to traffic arriving in the latter lane, and means for timing such interruption of right of way to both lanes to provide an ultimate length of time sufficient to permit a unit of traffic to clear through the zone of interference but to reduce the time of interruption of right of way to both lanes from such ultimate length in accordance with the amount of time which may have elapsed from the arrival of the last vehicle having right of way on one lane before the arrival of the first vehicle on the other lane while right of way is interrupted in the latter lane.

3. A traffic control system for the accord of right of way alternately to two approaches to a relatively long zone of interference, including means according right of way to either one approach responsive to traffic arriving therein and transferring right of way to the other approach in response to traffic in the latter approach,

means providing a short period of extension of right of way following the arrival of each of a series of vehicles on one approach while right of way is accorded thereto, means providing an overall clearance time period following the arrival of each such vehicle on said one approach with such overall clearance time period of considerably greater length than the right of way extension period, and means to interrupt right of way in the first approach while maintaining interruption of right of way in the second approach in response to the arrival of the first vehicle on said second approach upon termination of said right of way extension period on the first approach, and means determining the time length of such interruption of right of way to both approaches in accordance with the difference between the overall clearance time and the right of way extension time.

4. A traffic control system for two approaches to a relatively long zone of traffic interference, including a signal controller to accord right of way alternately to the two approaches responsive to traffic in the respective approaches, means forming a part of said controller to time each such accord of right of way and to provide a short period of extension of such right of way on either one approach following the arrival of a vehicle on said one approach while right of way is accorded to said one approach, and means providing an overall clearance time period following the arrival of such vehicle with such clearance time period of considerably greater length than the right of way extension time period, means to interrupt right of way the said one approach while maintaining interruption of right of way in the second approach at completion of such extension period in response to the arrival of the first vehicle on the second approach while right of way is interrupted therein, and means controlling the last named means to determine the time length of such interruption of right of way to both approaches in accordance with the difference between the overall clearance time period and the right of way extension time period.

5. A traffic control system for two approaches to a relatively long zone of traffic interference, including a right of way controller for accord of right of way alternately to the respective approaches in response to traffic on the respective approaches, a timer for controlling the time of such accord of right of way and having a relatively short time period for prolongation of right of way from the arrival of each vehicle arriving in one approach while right of way is accorded thereto and at the end of such time period to interrupt right of way on said one approach in response to traffic arriving on the second approach, a second timer to time a longer time period than the first mentioned period from the arrival of each vehicle having the right of way on said one approach and of sufficient time length to permit such arriving vehicles to clear through the entire zone of interference, and means controlled by said second timer to delay accord of right of way to said second approach in response to arrival of the first vehicle in said second approach so that a period of interruption of right of way to both lanes will ensue between termination of the time period of the first timer and termination of the time period of the second timer but only of sufficient length to clear the last vehicle arriving with the right of way on said one approach.

6. A traffic control system for interfering traffic lanes in which there is a relatively long zone of interference between said lanes, including go and stop traffic signals for the respective lanes, 5 signal control mechanism having alternate control positions for operating the respective go signals for the lanes one at a time while operating a stop signal to the other lane, timing means for maintaining said control mechanism in one position to operate the go signal for one lane for a minimum time period and for prolonging such operation for a short time period from the arrival of each of a series of vehicles on said one lane while such go signal is so operated, means 10 responsive to a vehicle arriving on the other lane and to termination of said short time period to operate said mechanism to its other position, and operate the stop signal on said first lane, and further timing means timing a further time period longer than said short time period from the arrival of each of said series of vehicles on said one lane to maintain operation of the stop signal in the second lane and to delay operation of the go signal in said second lane in the said other position of said signal mechanism for a sufficient 15 time to permit the last vehicle arriving on said one lane to clear the zone of interference.

7. A traffic control system for interfering traffic lanes in which there is a relatively long zone of interference between such lanes, including 20 green, yellow and red traffic signals for the respective lanes, traffic signal control mechanism for displaying said green signal to one of the lanes at a time and the red signal concurrently to the other lane, and for displaying the yellow signal after the green signal and before the red signal, timing means for controlling the time of display of the green signal for a minimum period and for prolonging said display period for a short 25 period following each of a series of vehicles arriving in said one lane, means responsive to arrival of a vehicle in the second lane while the green signal is displayed in the first lane to operate said signal mechanism to terminate display 30 of the green signal in said first lane and to initiate display of the yellow signal therein upon termination of the last of said short periods of prolongation, timing means to terminate the display of the yellow signal after a brief period and thereupon to display the red signal in said one lane, and further timing means to time a period following each of said series of vehicles arriving in 35 said first lane and extending over said yellow period and to maintain the red signal displayed 40 in said second lane while the red signal is also displayed in said first lane for a sufficient time after the end of said yellow period to permit the last of said series of vehicles on said first lane to clear through the zone of interference, and thereupon to terminate the display of red signal 45 in said second lane and substitute the display of the green signal therein.

8. A traffic control system for two approaches to a relatively long zone of traffic interference, 50 including signalling means for according and interrupting right of way to the respective approaches, traffic actuated means in the respective approaches to be actuated by traffic proceeding toward the said signalling means and said zone of interference, signal operating mechanism connected to said signalling means and said traffic actuated means for operating said signalling means to accord right of way to one approach and interrupt right of way to the other approach 55 in response to traffic actuation in the first ap-

proach, means forming a part of said mechanism to maintain right of way in said first approach for a short time extension period following each of a series of actuations of the traffic actuated means in said first approach by several units of traffic, timing means for timing a longer time period following each of such series of traffic actuations, means for terminating accord of right of way to said first approach by such signalling means upon expiration of said short time period and responsive to traffic actuation in the second approach, and means for interrupting right of way in said first approach by said signals following termination of right of way and for maintaining interruption of right of way in said second approach until completion of said longer time period before according right of way to said second approach responsive to actuations therein, whereby accord of right of way to said second approach will be delayed after interruption of right of way to said first approach for sufficient time only to clear the last unit of traffic entering the zone of interference from said first approach.

9. In a traffic signal control system for two mutually interfering traffic lanes, signalling means for according and interrupting right of way on the lanes, traffic actuatable means in the lanes, control means connected to the signalling means and to the traffic actuatable means and responsive to actuation of the traffic actuated means in one of the lanes to cause the signalling means to interrupt right of way on the other lane and to accord right of way to said one lane for at least a predetermined minimum period, means responsive to actuation of the traffic actuated means on said other lane to cause the signalling means to interrupt right of way on said one lane and to accord right of way to said other lane after expiration of the minimum right of way period on said one lane, timer means for timing an overall clearance period of sufficient length for a unit of traffic on said one lane to clear the other interfering lane and connected to have its timing initiated by actuation of the traffic actuated means on said one lane during the right of way period thereon, and means for causing the signalling means to maintain interruption of right of way on said opposing lane and to delay according of right of way to said opposing lane after completion of said minimum right of way period and after actuation of the traffic actuated means in said opposing lane until the clearance period of said timer means has been completed.

10. In a traffic signal control system for two mutually interfering traffic lanes, signalling means for according and interrupting right of way on the lanes, traffic actuatable means in the lanes, control means connected to the signalling means and to the traffic actuatable means and responsive to actuation of the traffic actuated means in one of the lanes to cause the signalling means to interrupt right of way on the other lane and to accord right of way to said one lane for at least a predetermined minimum period, means responsive to actuation of the traffic actuated means on said other lane to cause the signalling means to interrupt right of way on said one lane and to accord right of way to said other lane after expiration of the minimum right of way period on said one lane, timer means for timing an overall clearance period of sufficient length for a unit of traffic on said one lane to clear the other interfering lane, means for initiating operation of said timer means by actuation of the traffic actu-

ated means on said one lane during the right of way period thereon and for resetting operation of said timer means for restarting its timing period by further actuations within the right of way period thereon, and means for causing the signalling means to maintain interruption of right of way on said opposing lane and to delay according of right of way to said opposing lane after completion of said minimum right of way period and after actuation of the traffic actuated means in said opposing lane until the clearance period of said timer means has been completed.

11. In a traffic control system for two mutually interfering traffic lanes, signalling means for according and interrupting right of way to the lanes, traffic actuatable means in the lanes, control means connected to said signalling means and traffic actuated means and responsive to actuation of the traffic actuated means in one of the lanes to cause the signalling means to interrupt right of way on the opposing lane and to accord right of way to said one lane for at least the sum of the duration of a fixed initial interval and a vehicle interval, means responsive to actuation of the traffic actuated means on said one lane during said vehicle interval to prolong accord of right of way for a further vehicle interval, means responsive to actuation of the traffic actuated means on said opposing lane while right of way is on said one lane to cause transfer of accord of right of way to said opposing lane at the end of said further vehicle interval, timer means for timing an overall clearance time period in which a unit of traffic on said one lane entering the interference area during the right of way period for said one lane may pass entirely through the area, means for initiating operation of said timer at the start of said vehicle interval, means responsive to traffic actuation on said one lane within said vehicle interval to reset said timer to assure a full period for the actuating unit of traffic to clear the area, means for maintaining the interruption of right of way on said opposing lane after traffic actuation of the traffic actuated means therein and completion of said vehicle interval until the clearance period of said timer has been completed.

12. In a traffic control system for mutually interfering traffic lanes having signalling means for displaying accord and interruption of right of way to the lanes, traffic actuated means in the approach of each of the lanes to the area of interference, control means connected to the traffic actuated means and to the signalling means and operable responsive to actuation of the traffic actuated means in one of the lanes to cause the signalling means to accord of right of way to only said one of the lanes for at least a minimum period, means responsive to actuation of the traffic actuated means in another lane to cause transfer of accord of right of way to said another lane after the minimum period on said one lane, means operative while right of way is accorded on said one lane, in response to traffic actuation of the traffic actuated means on said one lane to time an overall clearance period in which the actuating unit of traffic will be assured time to pass entirely through the interference area and means for preventing the signalling means from according right of way to said another lane in response to actuation of the traffic actuated means therein until the timing means has completed its clearance time period.

13. In a traffic control system for two mutually interfering traffic lanes including signalling

means for displaying accord and interruption of right of way to the lanes, traffic actuatable means in the approaches of the lanes to an area in which they are mutually interfering, control means connected to the signalling means and to the traffic actuated means and responsive to actuation of the traffic actuated means in one lane to cause the signalling means to accord right of way to said one lane and to interrupt right of way on the opposing lane for at least a predetermined minimum period, and for a further extension period by further actuation during said minimum period, means including a timer initiated by actuation of the traffic actuated means in said one lane while right of way is on said one lane to time an overall clearance period in which the unit of traffic causing the actuation may pass entirely through the interference area, means responsive to actuation of the traffic actuated means in said opposing lane while right of way is on said one lane to cause the signalling means to interrupt right of way on said one lane after the minimum period while maintaining right of way interrupted on said opposing lane and to cause accord of right of way to said opposing lane only upon expiration of said clearance period, and means responsive to such actuation in said opposing lane to provide a maximum time limit to such further extension by such further actuation.

14. In a traffic controlled system for the accord of right of way alternately to two approaches to a relatively long zone of traffic interference in response to traffic on the respective approaches in which a series of short periods of extension of right of way are provided for a series of relatively closely spaced vehicles arriving on one approach while right of way is accorded thereto, and in which right of way is interrupted in said one approach upon termination of such extension period in response to the arrival of a vehicle on the other approach, means delaying accord of right of way to said second approach in response to said vehicles therein after such interruption of right of way in the first approach, a timing device to control said last named means so as to terminate such interruption of right of way to both approaches upon completion of its time period, and means connecting said timing device to start a timing period from the arrival of each of said series of vehicles on said one approach, whereby accord of right of way to the second approach in response to a vehicle therein will be delayed following the last vehicle to arrive on the first approach for a sufficient time to clear said last vehicle through the zone of interference.

15. In a traffic control system for accord of right of way alternately to two approaches to a relatively long zone of interference responsive to traffic in the respective approaches, timing means actuated by traffic to time a short period follow-

ing traffic actuation on one approach while right of way is accorded thereto and to terminate accord of right of way thereto at the end of such period responsive only to traffic in the opposite approach, and a second timing means actuated by traffic for timing a longer period following such actuation in said one approach having the right of way to maintain interruption of right of way in both approaches for a sufficient time period following such termination of right of way in said first approach to permit the last unit of traffic from said first approach to clear through the entire zone of interference.

16. A vehicle traffic control system for two interfering traffic lanes in which there is a relatively long zone of interference between said lanes, including go and stop traffic signal circuits for the respective lanes, signal circuit switching mechanism having alternate control positions for said circuits including one position for normally energizing the go signal for one line and the stop signal for the second lane and a second position for normally energizing the go signal for the second lane and the stop signal for the first lane, traffic actuatable relay means individual to the respective lanes, a resettable time switch having a short timing period, electrical operating means controlled by said time switch and by the traffic actuated relay of the second lane in such one position to operate said mechanism to its second position at completion of said short timing period responsive to actuation of said relay, a second resettable time switch having a considerably longer timing period than the first time switch, control circuits for said time switches connected with said mechanism and said traffic actuatable relay means to reset both of said time switches to restart their timing responsive to each traffic actuation on said first lane in the first position of said mechanism, relay means interposed between said mechanism and said signal circuits and connected to said mechanism to be operated by operation of said mechanism from said first position to said second position to interrupt the normal energization of the go signal and to energize the stop signal for the second lane in the second position when so operated, and a control circuit for the last named relay means controlled by said second time switch to maintain said last named relay means so operated until completion of timing by said second time switch and thereupon to release the relay means to restore the normal energization of the signals in said second position, whereby the last vehicle arriving on said one lane will be provided time to clear the zone of interference before energization of the go signal for the second lane.

HARRY A. WILCOX.
JOHN L. BARKER.

CERTIFICATE OF CORRECTION.

Patent No. 2,249,100.

July 15, 1941.

HARRY A. WILCOX, ET AL.

It is hereby certified that error appears in the printed specification of the above numbered patent requiring correction as follows: Page 5, first column, line 48, after "position 1" and before the period insert --by a ratcheting arrangement (not shown)--; page 7, second column, line 10, for "lead 323" read --lead 23--; and that the said Letters Patent should be read with this correction therein that the same may conform to the record of the case in the Patent Office.

Signed and sealed this 28th day of April, A. D. 1942.

Henry Van Arsdale,

Acting Commissioner of Patents.

(Seal)
